GIN OR SIMILAR MACHINE

Richard W. Starke, Atlanta, and Redding Sims, Washington, Ga., and James C. Quinn, Arlington, Tex., assignors to Butters Manufacturing Company, Atlanta, Ga., a corporation of Georgia

Application June 23, 1930, Serial No. 463,014

23 Claims. (Cl. 19—55)

This invention relates to improvements in gins and proposes improvements which are applicable both to gins and to linter gins, more often referred to simply as linters.

5 The invention is illustrated in connection with machines of the latter class for the satisfactory use of which it is important that the saws, the ribs, the float and the brush operate in a certain relation to one another. The saws, when new, have a diameter usually of 12½ inches. As they are resharpened from time to time their diameter is, of course, reduced, the metal being cut away or otherwise removed by the resharpening; and the reduction of the diameter from such cause 10 may be carried as far as two inches or slightly more. Obviously with such reduction in the diameter of the saws, the relation among the parts mentioned, that is to say the saws, ribs, float and brush, is varied and such variation, unless suitably corrected or compensated, impairs the operation of the linter. Heretofore, it has been proposed to effect this correction or compensation by 15 separate manual adjustments of the shafts of the saws, float and brush. Thus the shaft or mandrel of the gang of saws has been shimmed up or otherwise raised, the breast in which the float is mounted has been lowered and the shaft of the brush has been shifted laterally in connection with necessary adjustments of the positions of the mote, wind and partition boards. The objection to this proceeding is that it requires a very serious outlay of time and labor and does not necessarily maintain the efficient working relation of the parts.

20 35 This efficient relation, which, of course, is established at the start of the operation of the linter, is one wherein the brush has a suitable running clearance beyond the peripheries of the saws and wherein the saws have a maximum projection through the ribs to approximately within $\frac{1}{8}$ of an inch of the float. It is this relation which is difficult to maintain by the known methods of adjustment.

The principal object of the invention is to enable the required correction or compensation to be made in a few moments of time, with negligible effort, and with certainty in securing effective results, that is to say in maintaining the efficient working relation of the parts. By the employment of the features of the present invention a single operation is substituted for the operations described and in all cases the parts are maintained in the described efficient relation. More exactly, the present improvements accomplish the same essential relative adjustments

among the parts as have heretofore been accomplished but do so by causing these adjustments to be produced automatically and with certainty and accuracy by the manual operation of a single controlling element. Such manual operation is performed in a few moments of time and involves merely the turning of a hand wheel or equivalent part so that practically no expenditure of labor is required.

5 The breast, as heretofore, is hinged on the frame of the linter so that it may be raised or lowered to provide for the removal or replacement of the gang of saws; but in the present improvement this hinged mounting of the breast is additionally utilized for the purpose of a phase of the adjustments.

The adjustments in their entirety involve the actual movements of two centers and the relative movements of three centers. Of the two active movements the first is of the center provided by the saw mandrel, the movement whereof is upward along a radial line and toward the division board, thus keeping the saws approximately tangent to the brush at all times, and the second is of the center provided by the shaft of the float, the movement of which is in an arc having as its center the hinge of the breast. The radial line along which the saw mandrel is adjusted starts from the original position of such mandrel in which in present types of linters it is centered horizontally with relation to the brush shaft and is preferably at an angle of thirty-six degrees to the horizontal although there is a slight tolerance either way. The adjustments of the breast and the saw mandrel may be effected 30 in connection with one another or, if desired, and as will be explained later in detail, may be effected individually and independently.

A further object is to provide for the ready initial regulation or adjustment of the clearance 40 between the float and the saws, as, for example, by increasing such clearance in case it be desired to cut down the production of lint and to enable the particular clearance thus provided for to be automatically maintained in subsequent 45 adjustments of the position of the saw mandrel so long as the same production requirements may be imposed.

The same incidental reduction of the diameters 50 of the saws with resultant necessity for correction or compensation arises also in the case of gins which, similarly to linters, are provided with brushes for co-operation with the saws and in which adjustment of the brushes or the air nozzles are required from time to time in order to main- 55

tain the proper working relation of the saws. Certain features of the invention are, therefore, also applicable to gins and with the purposes and advantages described.

5 With the above objects and characteristics in view the invention consists generally in novel features of construction, combination and relation which will be pointed out in detail as the description proceeds.

10 An embodiment of the invention is illustrated in the accompanying drawings, in which:

Figure 1 is a vertical sectional view in a plane at right angles to the axes of the saw mandrel, float and brush shafts.

15 Figure 2 is a horizontal section on the line 2—4 of Figure 1 showing parts at one end of the machine.

Figure 3 is a detail section on the line 3—3 of Figure 2.

20 Figure 4 is a horizontal section on the line 2—4 of Figure 1 showing parts at the end of the machine opposite to that shown in Figure 2.

Figure 5 is a detail sectional view on the line 5—5 of Figure 4.

25 Figure 6 is a detail sectional view on the line 6—6 of Figure 5.

Figure 7 is a detail sectional view on the line 7—7 of Figure 1.

30 Figures 8 and 9 are perspective views of co-operating guide and slide plates employed as elements of the mechanism for adjusting the position of the linter breast.

Figure 10 is a detail plane view somewhat enlarged showing a scale and co-operating pointer 35 for indicating the adjustment of the machine with reference to variations in saw diameters.

The linter shown in the accompanying drawings is of a well known type and its details, such as the wind and division plates, the mote board, features connected therewith and other details possessing no novelty will require no specific description, being at once apparent to those skilled in the art.

45 The parts in connection with which the present improvements are applied are the saws 1 mounted on the mandrel 2, the brush 3 mounted on the shaft 4, and the breast which includes the front 5, roll box 6, float 7, ribs 8, upper rib rail 9 and lower rib rail 10, the top of the breast being 50 hinged as at 11 to a frame bar 12 whereby the breast may be raised from its operative position to permit a gang of saws to be set in or removed from operative position.

55 In respect to the above structural details we have thus far described nothing new.

The linter frame includes end standards 13 which support the bearings 14 for the saw mandrel 2 and the bearings 15 for the brush shaft 4.

60 The saw mandrel 2 is, in present types of linters, originally centered horizontally or substantially so with relation to the brush shaft 4 and, according to the invention, is adjustable, as a center, along a radial path inclined upward and inward at an angle to the horizontal of the order of 65 thirty-six degrees. For the purpose of such adjustment the bearings 14 are mounted upon supporting blocks 16 in turn supported on the upper bars 17 of the standard 13 and those parts 17a of such bars on which the blocks 16 rest are utilized as guide rails along which said blocks may be moved to effect the adjustment of the saw mandrel along the described radial path. Hence the rails 17a have an inward and upward inclination conforming to said radial path and the lower 70 faces of the blocks 16 are inclined in conformity 75

to said rails whereby said blocks in any position thereof will have stable support on said rails and will be readily movable upward along the same. To aid in holding the blocks 16 in the positions to which they may be adjusted each rail 17a may be formed with a longitudinal slot 17b to accommodate cap screws 18, the shanks of which are engaged in threaded sockets 19 provided with or formed on the inclined base of each block 16 and the caps of which engage frictionally against the under side of the upper flange of the rails. It is also preferred to provide along the upper face of each rail a longitudinal recess 17c and to provide the base of each block 16 with a longitudinal rib 16a for engagement in the recess 17c of the companion rail, the recesses 17c and the ribs 16a cooperating in positively guiding the blocks 16 along the rails.

When adjustment of the blocks 16 is required the screws 18 are loosened in order that said blocks 20 may be freely movable along the rails 17a and when said blocks have been moved to the position desired said screws are then tightened in order to secure or aid in securing the blocks in such position.

25 The mechanism for effecting the movement of the blocks 16 along the rails 17a and the resultant adjustment of the position of the saw mandrel preferably and conveniently includes screw operated wedges 20 having vertical inclined or cam 30 engaging faces 21. The wedges 20 directly cooperate with lugs 22 formed or provided on the blocks 16 and their cam faces 21 bear against conforming cam faces 23 on said lugs. The wedges 20 and lugs 22 are so arranged relatively to one 35 another that inward movement of said wedges, that is to say movement of said wedges toward one another, will effect upward movement of the blocks 16 along the rails 17a. Such movements of the wedges 20 are effected by a transverse shaft 40 24 having at or near its respective opposite ends right and left hand threads 25, one set of threads for each wedge. The wedges are formed or provided with nuts 26 for engagement with the respective sets of threads 25. As shown the nuts 26 project downward from said wedges and the bar 17 is formed adjacent the lower ends of the rails 17a with recesses 27 which provide clearances for the nuts 26. The wedges 20 may react against any appropriate parts. For this purpose the adjacent vertical legs 28 of the standards 13 may be utilized to take the thrust of said wedges. The legs 28 are preferably each provided at their upper ends with horizontal recesses 29 and the wedges are provided with guide ribs 30 for engagement 50 in said recesses. The shaft 24 is suitably journaled in bearings incorporated with or mounted on bars of the linter frame and projects beyond said frame at one end, its projecting portion being provided with a hand wheel 31 by which said shaft may be rotated in order to effect the movement of the wedges 20 and the resultant movement of the blocks 16, thereby to adjust the position of the saw mandrel.

When the saw mandrel is thus adjusted it is 65 in most cases necessary or desirable to effect a conforming adjustment of the linter breast in order that the proper clearance between the peripheries of the saws 1 and the float 7 and also the proper relative location of the ginning point (i. e. the point at which the saw teeth after passing beyond the float pass between the ribs 8) may be maintained. For this phase of the adjustment the hinge connections 11 may be utilized. The linter breast, in addition to the hinge 70 75

connections 11, has support from a transverse frame bar 32 which may extend between and be secured to the legs 28 of the standard 13. The supporting elements for the breast may consist of posts 33 carried by the frame bar 32 and which project at a suitable angle upward and outward from said bar, the lower rib rail 10 resting against the upper ends of said posts, two of which are preferably employed, one located somewhat near each end of the frame bar 32. The posts 33 are adjustable in the direction of their axes in order to provide for raising or lowering the breast about its hinges 11 with resultant shifting of the shaft of the float 7 as a center. Such movements of the posts 33 to adjust the position of the float are preferably, and as a feature of the invention, effected automatically in connection with the operation of the shaft 24 to effect the movements of the wedges 20.

The bar 32 is formed with openings 34 through which the posts 33 extend and by which they are guided and laterally supported. Behind said openings said bar carries plates 35 which are mounted for sliding movement lengthwise of said bar or transversely of the linter. The plates 35 are directly supported by stationary frames 36 whose bars outline rectangular openings 37, the frames 36 being suitably secured to the bar 32. The upper and lower bars of each frame 36 are rabbeted along their inner faces to provide shoulders 38 by which the plates 35 are supported and guided. The plates 35 are formed with angular extensions 39 which project through the openings 37 and have bottom flanges 40 so formed that they are operative as cams in controlling the movements of the posts 33. The flanges 40 in their transverse direction have a suitable angle to the horizontal which is conformable to the angle at which the posts 33 extend and in their longitudinal direction are inclined inward and upward and at an angle which will provide for the movement of said posts at a rate co-ordinated to the movement of the wedges 20 whereby the adjustment of the position of the float will always be proportionate to or co-ordinated with the adjustment of the position of the saw mandrel.

The flanges 40 of the respective plates 35 preferably extend inwardly and upwardly in relatively opposite directions in order that the lateral stresses incident to the thrusts which they take may be balanced or opposed.

The plates 35 are preferably operated similarly to the wedges 20, that is to say by means of a transverse shaft 41 arranged above and parallel to the shaft 24 and having oppositely threaded portions 42 for co-operation with the respective plates 35. The extensions 39 of the plates 35 are provided with depending nuts 43 for engagement with the respective oppositely threaded portions of the shaft 41. It will be apparent that as the shaft 41 is rotated the plates 35 will be moved in opposite directions and according to their directions of movement will raise or permit the lowering by gravity of the supporting posts 33 with corresponding movements of the breast about the hinges 11. Thus when the saw mandrel is adjusted upwardly and inwardly the breast is proportionately lowered.

The shaft 41 is preferably operated from the shaft 24 through connections which, however, may be regulated to permit independent operation of either of said shafts. Thus the shaft 41 at one end projects through a clearance opening 41a in one of the lugs 26 and its projecting portion has fast thereon a pinion 45 and the

shaft 24 has loosely mounted thereon a pinion 44 which meshes with the pinion 45, said pinions being enclosed in a suitable housing 46 through and beyond which said shafts project. The shaft 24 carries adjacent the hand wheel 31 a slidably keyed clutch element 47 having projections 48 for engagement in recesses in the hub of the pinion 44, the adjacent wall of the casing 46 having an opening through which the end of the clutch element may pass. When the clutch element 47 is engaged with the pinion 44 said pinion will, of course, rotate with the shaft 24 and through the pinion 45 will operate the shaft 41. When the clutch element 47 is disengaged from the pinion 44 the latter will be free on the shaft 24 and hence said shaft may be rotated without effecting the operation of the shaft 41. With the pinion 47 disengaged from the pinion 44 the shaft 41 may also be operated independently of the shaft 24 by means of a suitable crank or handle applied to its squared end 49.

It sometimes happens that a mill operator, for one reason or another will desire to produce less than the maximum lint capacity of the machine or may desire to operate with less expenditure of power. Such regulation of the quantity of lint produced by the machine or the limitation of the power required for its operation can be had by varying the clearance between the saws and the float. Hence the provision for the permissible operation of the shafts 24 and 41 independently of one another provides for such variation in the clearance between the saws and the float and it follows that the clearance may initially be regulated as desired and thereafter automatically maintained in connection with the adjustment of the saws by causing the shaft 41 to be rotated from the shaft 24.

The required extent of the adjustment of the saw mandrel in a particular case can be determined by the number of turns of the shaft 24 as effected by the hand wheel 31. However, it is preferable to provide suitable means for indicating the position of the saw mandrel with reference to saws of any given diameter within the range of adjustment. A convenient mechanism for this purpose consists of a rack bar 50 mounted on the upper face of one of the wedges 20 and engages a toothed sector 51 provided as a tail piece on the pointer 52 pivotally mounted on the upper face of the adjacent leg 28, the end of the pointer traversing a scale 53 which is suitably calibrated with indications of the saw diameters, these calibrations being shown in the drawings in degrees of $\frac{1}{8}$ of an inch for diameters from a maximum of $12\frac{1}{2}$ inches to a minimum of 11 inches. If the construction of the linter is otherwise suitable, saws of smaller diameters may be used and the calibrations of the scale 53 may be extended accordingly.

The use of the linter will ordinarily be started with saws of maximum diameter, the standard maximum being $12\frac{1}{2}$ inches. As these are reduced in diameter by repeated sharpening their center, i. e. the saw mandrel, must be set nearer the brush in order that the proper running clearance may be maintained. This adjustment is effected by the unisonous movement of the wedges 20 in the manner described. Since the maximum or other determined clearance between the saws and the float must in all cases be maintained in order to insure the continued efficient operation of the linter, the saws and the float must also be relatively adjusted in connection with the relative adjustment of the saws and the

brush. The relative adjustment of the saws and the float is effected by lowering the breast, this operation being accomplished by the unisonous movement of the slide plates 35 in directions such that the posts 33 ride relatively downward along the cams provided by the flanges 40 of the slide plate extensions 39.

While the two adjustments could, of course, be effected separately, they are preferably effected in the manner described, that is to say by operating the shaft 41 from the shaft 24 whereby the unisonous movement of the slide plates 35 is so synchronized with the unisonous movements of the cams 20 that the adjustment of the float will at all times be exactly proportionate to and coordinated with the adjustment of the saw mandrel; hence when the saw mandrel has been adjusted to the required position the float, as part and parcel of the same manual operation, will have been brought to the exact position required for its continued proper co-operation with the saws. The adjustments described are effected with certainty and exactness whereby the proper clearances between the saws and the brush on the one hand and the saws and the float on the other hand are at all times maintained and with no substantial alteration of the ginning point. The inclined path along which the saw mandrel is adjusted moreover insures the proper tangential relation at all times of the saws to the brush and permits of the lowering of the breast about its hinges 11 to effect the adjustment of the float without any interference between the saws and the upper and lower rib rails. Since all adjustments may be effected simultaneously, accurately and in co-ordinated relation simply by turning the hand wheel 31 with resultant rotation of the shafts 24 and 41 they require only negligible effort and may be completed in a few moments of time, the moving pointer 52 by its coincidence with the scale marking corresponding to the diameter of the particular saws being available to indicate when the adjustment has been completed. In making these adjustments to compensate for changes from saws of greater diameter to saws of less diameter the saws may be set in position either before or after the adjustment is made. The breast may, of course, be swung back on its hinges while the adjustments are being made and lowered after they have been completed, its position in any case being controlled by the posts 33 as held by and upon the cam flanges 40.

Assuming that the saws of a gang to be put into the linter are of greater diameter than the saws of a gang just previously used, the saws and the float are adjusted in the manner described but in opposite directions, that is to say the shaft 24 is rotated to move the cams 20 outward and permit the blocks 16 and bearings 14 attached thereto to slide downward along the rails 17a and the shaft 41 is rotated to effect such movement of the slide plates 35 as will cause their cam flanges 40 to move the posts 33 outward, thereby to support the breast at a higher elevation. Such adjustments having been made the gang of saws of greater diameter may be set in position and the breast lowered to the position determined by the posts 33 as held by and upon the cam flanges 40.

It will, of course, be apparent that the time from the operation of the linter lost in consequence of the adjustments described is almost negligible and hence that the production capacity of the linter, based on the time of its op-

eration, is effectively increased, this marked economy being obtained along with an advantageous economy of labor since but a few moments of time of but a single operator is all that is required, no adjustment of any of the other parts, i. e. division and wind plates and mote board, being necessary.

While we have herein described in detail a single embodiment of the invention it will, of course, be understood that the operations essentially contemplated can be carried out by varying forms of mechanism all falling within the scope of the appended claims and hence that the description herein of detail features is for purposes of exposition and is not to be regarded as imposing any limitations upon the claims not inherent in their terms.

Having fully described our invention, we claim:

1. In a machine of the type set forth the combination with the saws, the saw mandrel and the bearings for said mandrel, of rails upon which said bearings are mounted for sliding movement, said rails being upwardly and inwardly inclined at an angle which will permit adjustments of the position of the saw mandrel to compensate for variations in the diameters of the saws without impairing the operative relation of the saws to the other parts of the machine and means for moving said bearings along said rails and in either direction of the inclined path which said rails provide, said means including movable wedges and lugs associated with said bearings and against which said wedges re-act.

2. In a machine of the type set forth the combination with the saws, the saw mandrel and the bearings for said mandrel, of rails upon which said bearings are mounted for sliding movement, said rails being upwardly and inwardly inclined at an angle which will permit adjustments of the position of the saw mandrel to compensate for variations in the diameters of the saws without impairing the operative relation of the saws to the other parts of the machine and means for moving said bearings along said rails and in either direction of the inclined path which said rails provide, said means including movable wedges and lugs associated with said bearings and against which said wedges re-act, and mechanism for operating said wedges unisonously.

3. In a machine of the type set forth the combination with the saws, the saw mandrel and the bearings for said mandrel, of rails upon which said bearings are mounted for sliding movement, said rails being upwardly and inwardly inclined at an angle which will permit adjustments of the position of the saw mandrel to compensate for variations in the diameters of the saws without impairing the operative relation of the saws to the other parts of the machine and means for moving said bearings along said rails and in either direction of the inclined path which said rails provide, said means including movable wedges and lugs associated with said bearings and against which said wedges re-act, and mechanism for operating said wedges unisonously including a transverse shaft having threaded portions, one for each wedge and nuts on said wedges co-operating with the respective threaded portions of said shaft.

4. In a machine of the type set forth the combination with the saws, the saw mandrel and the bearings for said mandrel, of rails upon which said bearings are mounted for sliding movement, said rails being upwardly and inwardly inclined at an angle which will permit adjustments of

- the position of the saw mandrel to compensate for variations in the diameters of the saws without impairing the operative relation of the saws to the other parts of the machine and means for 5 moving said bearings along said rails and in either direction of the inclined path which said rails provide, said means including movable wedges and lugs associated with said bearings and against which said wedges re-act, and mechanism for operating said wedges unisonously including a transverse shaft having threaded portions, one for each wedge and nuts on said wedges co-operating with the respective threaded portions of said shaft, said wedges being movable 10 in relatively opposite directions to effect movements of said bearings in the same direction and the threaded portions of said shaft being oppositely directed.
5. In a machine of the type set forth the combination with the saws, the saw mandrel, the bearings for said mandrel, the brush which co-operates with the saws in approximately tangential relation thereto, the breast having the roll box into which the saws project and the float in 15 said roll box for co-operation with the saws, of means in co-operation with said bearings to provide for the adjustment of the position of said mandrel as a center along a radial path inclined inwardly and upwardly toward said brush whereby to compensate for variations in the diameters 20 of the saws and to maintain the tangential co-operative relation of the saws and the brush, a hinged mounting for the breast and means to provide for the adjustment of the breast about the center provided by said hinged mounting whereby the float may be shifted in connection with the 25 adjustment of the saws in order to maintain the proper co-operative relation between it and said saws.
40. 6. In a machine of the type set forth the combination with the saws, the saw mandrel, the bearings for said mandrel, the brush which co-operates with the saws in approximately tangential relation thereto, the breast having a roll box into which the saws project and the float in said 30 roll box for co-operation with the saws, of means providing a radial upwardly and inwardly inclined path of adjustment for said mandrel as a center whereby the saws may be positioned to compensate for variations in their diameters 35 while maintaining the tangential co-operative relation of the saws and the brush, means for providing a path of adjustment for the float along which the float may be set in a position co-ordinated to a particular position of the saws.
45. 7. In a machine of the type set forth the combination with the saws, the saw mandrel, the bearings for said mandrel, the brush which co-operates with the saws in approximately tangential relation thereto, the breast having a roll box into which the saws project and the float in said 40 roll box for co-operation with the saws, of means providing a radial upwardly and inwardly inclined path of adjustment for said mandrel as a center whereby the saws may be positioned to compensate for variations in their diameters 45 while maintaining the tangential co-operative relation of the saws and the brush, means for providing a path of adjustment for the float along which the float may be set in a position co-ordinated to a particular position of the saws, and means for simultaneously adjusting said mandrel and said float along their respective paths.
50. 8. In a machine of the type set forth the combination with the saws, the saw mandrel, the bearings for said mandrel, the brush which co-operates with the saws in approximately tangential relation thereto, the breast having the roll box into which the saws project and the float in said 50 roll box for co-operation with the saws, of means providing a radial upwardly and inwardly inclined path of adjustment for said mandrel as a center whereby the saws may be positioned to compensate for variations in their diameters 55 while maintaining the tangential co-operative relation of the saws and the brush, means for providing a path of adjustment for the float along which the float may be set in a position co-ordinated to a particular position of the saws, and means for simultaneously adjusting said mandrel and said float along their respective paths.
55. 9. In a machine of the type set forth, the combination with the saws, the saw mandrel, the bearings for said mandrel, the brush which co-operates with the saws in approximately tangential relation thereto, the breast having the roll box into which the saws project and the float in said 60 roll box for co-operation with the saws, of means providing a radial upwardly and inwardly inclined path of adjustment for said mandrel as a center whereby the saws may be positioned to compensate for variations in their diameters 65 while maintaining the tangential co-operative relation of the saws and the brush, means for providing a path of adjustment for the float along which the float may be set in a position co-ordinated to a particular position of the saws, and means for simultaneously adjusting said mandrel and said float along their respective paths.
70. 10. In a machine of the type set forth, the combination with the saws, the saw mandrel, the bearings for said mandrel, the brush which co-operates with the saws in approximately tangential relation thereto, the breast having the roll box into which the saws project and the float in said 70 roll box for co-operation with the saws, of means providing a radial upwardly and inwardly inclined path of adjustment for said mandrel as a center whereby the saws may be positioned to compensate for variations in their diameters 75 while maintaining the tangential co-operative re-

lation of the saws and the brush, means providing a path of adjustment for the float along which the float may be set in a position co-ordinated to a particular position of the saws, and means operable at will to effect independent or simultaneous adjustments of said mandrel and said float along their respective paths.

12. In a machine of the type set forth, the combination with the saws and the breast having a roll box into which the saws project and the float in said roll box for co-operation with the saws, of a hinged mounting for the breast and about which the breast is adjustable and means to support the breast and to provide for its adjustment about the said hinged mounting including axially slidable breast supporting posts, movably mounted cam elements to take the thrust of said posts and effect variations in their positions and mechanism for operating said cam elements.
13. In a machine of the type set forth, the combination with the saws and the breast having a roll box into which the saws project and the float in said roll box for co-operation with the saws, of a hinged mounting for the breast and about which the breast is adjustable and means to support the breast and to provide for its adjustment about the said hinged mounting including axially slidable breast supporting posts, slidably mounted plates having cam formations to take the thrust of the posts and to determine their positions, a shaft having threaded portions, and nuts carried by said plates for engagement with the threaded portions of said shaft.

35 14. In a machine of the type set forth, the combination with the saws, the saw mandrel, the bearings for said mandrel, the brush which co-operates with the saws in approximately tangential relation thereto, the breast having a roll box into which the saws project and a float in
40 said roll box for co-operation with the saws, of rails upon which said bearings are mounted for sliding movement, said rails being upwardly and inwardly inclined at an angle which will permit adjustment of the position of the saw mandrel to
45 compensate for variations in the diameters of the saws without impairing the operative relation of the saws to the other parts of the machine, means for moving said bearings along said rails in either direction of the inclined path
50 which said rails provide, said means including movable wedges, lugs associated with said bearings and against which said wedges re-act, a transverse shaft having threaded portions, one
55 for each wedge, and nuts on said wedges co-operating with the respective threaded portions of said shaft, a hinged mounting for said breast and about which the breast is adjustable in order that the position of the float may be co-ordinated to the position of the saws and means
60 providing for the support and adjustment of the breast including axially slidale supporting posts upon which the breast rests, slidale plates having cam portions to take the thrust of said posts and to determine their positions, a second transverse shaft having threaded portions, and nuts on said plates co-operating with the respective threaded portions of said second shaft.

15. In a machine of the type set forth, the combination with the saws, the saw mandrel, the bearings for said mandrel, the brush which co-operates with the saws in approximately tangential relation thereto, the breast having a roll box into which the saws project and a float in said roll box for co-operation with the saws, of rails upon which said bearings are mounted for

sliding movement, said rails being upwardly and inwardly inclined at an angle which will permit adjustment of the position of the saw mandrel to compensate for variations in the diameters of the saws without impairing the operative relation of the saws to the other parts of the machine, means for moving said bearings along said rails in either direction of the inclined path which said rails provide, said means including movable wedges, lugs associated with said bearings and against which said wedges re-act, a transverse shaft having threaded portions, one for each wedge, and nuts on said wedges co-operating with the respective threaded portions of said shaft, a hinged mounting for said breast and about which the breast is adjustable in order that the position of the float may be co-ordinated to the position of the saws, means providing for the support and adjustment of the breast including axially slideable supporting posts upon which the breast rests, slideable plates having cam portions to take the thrust of said posts and to determine their positions, a second transverse shaft having threaded portions, and nuts on said plates co-operating with the respective threaded portions of said second shaft and means for driving one of said shafts from the other. 10 15 20 25

16. In a machine of the type set forth, the combination with the saws, the saw mandrel, the bearings for said mandrel, the brush which co-operates with the saws in approximately tangential relation thereto, the breast having a roll box into which the saws project and a float in said roll box for co-operation with the saws, of rails upon which said bearings are mounted for sliding movement, said rails being upwardly and inwardly inclined at an angle which will permit adjustment of the position of the saw mandrel to compensate for variations in the diameters of the saws without impairing the operative relation of the saws to the other parts of the machine, means for moving said bearings along said rails in either direction of the inclined path which said rails provide, said means including movable wedges, lugs associated with said bearings and against which said wedges re-act, a transverse shaft having threaded portions, one for each wedge, and nuts on said wedges co-operating with the respective threaded portions of said shaft, a hinged mounting for said breast and about which the breast is adjustable in order that the position of the float may be co-ordinated to the position of the saws, means providing for the support and adjustment of the breast including axially slidable supporting posts upon which the breast rests, slidable plates having cam portions to take the thrust of said posts and to determine their positions, a second transverse shaft having threaded portions, and nuts on said plates co-operating with the respective threaded portions of said second shaft and means operable at will to provide for the operation of said shafts either independently of one another or in driving and driven relation to one another.

17. In a linter gin, the combination, with the
saws, the saw mandrel, and the bearings for said
mandrel of rails upon which said bearings are
mounted for sliding movement and which are
upwardly and inwardly inclined at an angle such
as will permit adjustments of the position of the
saw mandrel to compensate for variations in the
diameters of the saws without impairing the oper-
ative relation of the saws to the other parts of
the machine, mechanism for effecting such ad-
justments of the saw mandrel, and means in
75

- cluding relatively movable elements operable in connection with said mechanism for indicating at any moment the position of the saw mandrel corresponding to a particular diameter of the 5 saws.
18. In a linter gin the combination with a gratefall, saw cylinder and doffing means, of a support for the saw cylinder including saddles for the cylinder shaft, bolsters on which said 10 saddles are supported, means for shifting said bolsters to move the cylinder toward the gratefall and doffing means, said gratefall being pivotally mounted and including bars connected at one end by a crossbar, and means engaging 15 said crossbar for limiting the pivotal movement of the gratefall in one direction, said limiting means being movable concomitantly with the bolster shifting means.
19. In a linter gin the combination with a 20 gratefall, saw cylinder, a float roll disposed in cooperative relation to the saw cylinder, and doffing means, of a support for the saw cylinder including saddles for the cylinder shaft, bolsters on which said saddles are supported, a platform 25 having inclined surfaces upon which surfaces the bolsters are supported and over which the bolsters may advance toward said doffing means, movable means carried by said platform, which means engage one end of each bolster and prevent their movement away from said doffing means, means for advancing said preventing means and thereby causing said bolsters to move said cylinder toward said doffing means, and means operable by said advancing means for 30 simultaneously moving said float roll and gratefall in a pivotal path, whereby to effect a simultaneous adjustment of the float roll and gratefall relative to the saw cylinder.
20. In a linter gin the combination with a 35 gratefall, saw cylinder and doffing means, of a support for the saw cylinder including saddles for the cylinder shaft, bolsters on which said saddles are supported, a platform having inclined surfaces upon which surfaces the bolsters 40 are supported and over which the bolsters may advance toward said doffing means, movable means carried by said platform, which means engage one end of each bolster and prevent their movement away from said doffing means, and means for advancing said preventing means and thereby causing said bolsters to move said cylinder toward said gratefall and doffing means, said gratefall being pivotally mounted and including 45 spaced parallel bars connected at one end by a crossbar, and movable means carried by said 50
- platform for limiting the pivotal movement of the gratefall in one direction, said movable means being retracted by said advancing means to permit further pivotal movement of the gratefall in such direction. 5
21. In apparatus of the character described the combination with the saws, the saw cylinder and bearings for said cylinder, and doffing brush which cooperates with the saws in approximately tangential relation thereto, the breast unit including 10 the roll box into which the saws project and the float roll in said roll box for cooperation with the saws, of means providing a radial upwardly and inwardly inclined path of movement for said cylinder whereby the saws may be adjusted to 15 compensate for variations in their diameter while maintaining the tangential cooperative relation of the saws and doffing brush, and means providing a pivotal path of movement for the float roll whereby the position of the float roll relative to 20 the saws may be simultaneously adjusted to maintain its proper cooperative relative to the saws. 25
22. In a machine of the type set forth, the combination with the saws, the saw mandrel, doffing means and the breast having the roll box into which the saws project and the float in said roll box for cooperation with the saws, said parts having a normal working relation, of means for moving the saws relatively to said doffing means 30 and breast to compensate for variations in the diameters of the saws and means automatically operable upon actuation of said last named means for moving said breast in accordance with the movement of said saws, whereby to maintain the 35 normal working relation between said parts. 35
23. In a machine of the type set forth, the combination with the saws, the saw mandrel, doffing means and the breast having the roll box into which the saws project and the float in 40 said box for cooperation with the saws, said parts having a normal working relation, of means for moving the saws relatively to said doffing means and breast to compensate for variations in the diameters of the saws, said means including a 45 control element, means for moving said breast relatively to said saws and means operatively connecting said last named means and said element, whereby upon adjustment of the saws the breast is moved correspondingly to maintain the 50 normal working relation between said parts. 50
